UNITED STATES PATENT OFFICE.

KARL A. SUNDQUIST, OF BRIDGEPORT, CONNECTICUT; MAGDA E. NELSON, ADMINISTRATRIX OF SAID KARL A. SUNDQUIST, DECEASED, ASSIGNOR TO JOHAN O. SUNDQUIST, OF LULEA, SWEDEN.

WRITING MACHINE.

Application filed November 24, 1925. Serial No. 71,264.

This invention relates to a writing or drawing machine for advertising purposes, and the broad object of the invention is to provide a writing or drawing machine which will include a plate having a master groove, a groove follower and means for propelling the follower along the groove of the master plate, and a stylus adapted to travel with the groove follower to reproduce its movements.

A more specific object is to provide novel, improved and efficient means for positively propelling the follower along the master plate groove.

15 A further specific object is to provide a writing machine as stated, which will include mechanism whereby a plurality of master plates can be successively fed to and from a station or location in the machine to receive the follower.

20 A further specific object is to provide mechanism whereby the machine can have any desired number of plates the feed of each which is separately and automatically controlled, each plate being adapted to be fed to a station or location in the machine to receive the groove follower, to be fed from said station or location to make room for a succeeding plate when the follower shall have completed its traverse of a master plate at said station or location, and to be fed to a position in the machine ready to be re-presented to said station or location in its regular order of succession.

25 A further specific object is to provide in the machine an endless curtain or belt adapted to serve as a writing surface, and to provide means for advancing said writing surface at predetermined intervals.

30 40 And further specific objects are to provide in the machine means whereby said writing surface can be advanced a plurality of steps instead of a single step, and whereby there can be a feeding of a plurality of plates past the follower receiving station or location at the completion of the traverse by the follower of the groove of a plate, instead of the feeding of a single master plate from said station or location.

45 50 With the above objects in view, as well as others which will appear as the specification proceeds, the invention comprises the construction, arrangement and combination of

parts as now to be fully described and as hereinafter to be specifically claimed, it being understood that the disclosure herein is merely illustrative and meant in no way in a limiting sense, changes in details of construction and arrangement of parts being permissible so long as within the spirit of the invention and the scope of the appended claims.

In the accompanying drawing forming a part of this specification,

Fig. 1 is a front elevational view, partly in section, of a machine in which the features of the invention are incorporated;

Fig. 2 is a vertical sectional view thereof, as on line 2-2 in Fig. 1;

Fig. 3 is an enlarged sectional view detailing a master plate, a groove follower, means for propelling the follower along the groove of the master plate, a stylus, and an operative connection between the stylus and the follower and its propelling means;

Fig. 4 is a diagrammatic view detailing the manner in which the follower propelling means functions;

Fig. 5 is a fragmentary elevational view of a modified form of follower propelling means;

Fig. 6 is a sectional view, after the fashion of Fig. 3, detailing a master plate, a groove follower, and the follower propelling means of Fig. 5; and

Fig. 7 is an elevational view of a master plate and means whereby the writing surface could be advanced a plurality of steps and a plurality of plates could be fed past the follower receiving station or location at the completion of the traverse by the follower of the groove of a master plate.

With respect to the drawing and the numerals of reference thereon, 10 denotes a rectangular frame consisting of a base 11, side walls 12, rear wall 13, top wall 14, and front wall 15 having a cut-out portion 16. The portion of the front wall 15 below the cut-out portion 16 is in advance of the remainder of said front wall, and at the location, denoted 17, of the lower edge of the cut-out 16 said front wall is of extra thickness and is provided with a vertical slot 18 extending transversely of the frame for its width, the vertical slot 18 being for a purpose to be explained.

Numeral 19 denotes a vertical, front guide member secured to the top wall 14 as at 20 and extending transversely of the frame, the guide member 19 being desirably situated in the frame in about the manner as disclosed in Figs. 1 and 2, the side edges 21 of said member terminating in spaced relation to the side walls 12, and the lower portion 22 thereof being curved slightly rearwardly and terminating in spaced relation to the base 11 of the frame.

Numeral 23 represents a rear guide member secured to the side walls 12 of the frame in any suitable manner, as by the cross-pieces 24, and also extending transversely of the frame, the guide member 23 being desirably of about the width of the guide member 19 and being situated directly back of said member 19. The upper portion 25 of the guide member 23 is spaced from the guide member 19, is preferably vertical, and terminates in spaced relation to the top wall 14 of the frame. The vertical portion 25 merges in an oblique portion 26 extending downwardly and toward the guide member 19, and the oblique portion terminates in a vertical portion 27 parallel with and closely adjacent to the guide member 19. The lower end 28 of the guide member 23 desirably terminates a trifle short of the lower end of the guide member 19. See Fig. 2.

The guide member 19 and the vertical, upper portion 25 of the guide member 23 provide a storage space 29 for plates 30 each having a master groove 31, the guide member 19 and the oblique portion 26 of the guide member 23 provide a chute 32 into which the master plates are adapted to drop one at a time from said storage space, and the guide member 19 and the vertical, lower portion 27 of the guide member 23 provide a way 33 into which each master plate is adapted to pass from the chute 32.

Mechanism is provided for retaining a plurality of master plates 30 in the storage space 29 and for retaining a single master plate in the way 33 at a station or location 34 where a groove follower can enter the groove 31 of said plate in a manner to be explained. The mechanism for so retaining the plurality of plates and the single plate includes interconnected devices adapted to at predetermined intervals release a plate at said station or location 34 to allow the same to move by gravity out of the way 33, and to simultaneously release a plate in said storage space 29 to allow the same to pass to said station or location.

Of the master plate retaining and releasing mechanism, 35 indicates upper brackets having bearings 36 for spindles 37, and 38 represents lower brackets having bearings 39 for spindles 40. In Fig. 2 a bracket 35 is shown secured to the rear guide member 23, and in Fig. 1 a bracket 38 is shown se-

cured to a side wall 12. The brackets 35 and 38 at the left hand side of Fig. 1 (not shown) are similarly secured. Each spindle 37 and 40 has fixed to it an arm, denoted 41 and 42, respectively, and the arms 41 and 42 at each side of the machine are pivotally connected by a link 43. Each spindle 37 has fixed to it a suitable escapement pinion 44, the teeth of the pinion being desirably spaced at equal distances apart, and each spindle 40 has fixed to it a similar escapement pinion 45. A cylindrical surface 46 integral with the pinion 45 has depressions 47, there desirably being a depression 47 in alignment with each pinion tooth. See Figs. 1 and 2. The teeth of the pinions 44 are adapted to support the master plates in the storage space 29, and the teeth of the pinions 45 are adapted to support each master plate at the station or location 34, and to this end each master plate is provided with a pin 48 in the center of each of its opposite side edges, which pins are adapted to rest upon the opposed pinion teeth in the manner very clearly disclosed in Figs. 1 and 2. As shown more clearly in Fig. 2, the upper and lower ends of the master plates in the storage space 29 are adapted to engage the portion 25 of the guide member 23 and the guide member 19, respectively, while a tooth of each of the opposed pinions 44 is engaged by the pins 48 of the bottom master plate in said storage space to thus support all of the plates in oblique position in the storage space. 49 are U-shaped brackets secured to the portion 27 of the guide member 23 at a location beneath the depression 47. A rod 50 slidable in the arms of each U-shaped bracket 49 has its upper end spring pressed into a depression 47 as by a coil spring 51 upon the rod and between the legs of the bracket, and has upon its lower end a head 52. Clearly, the rods 50 thus lock the spindles 37 and 40 which have the escapement pinions 44 and 45 against rotation and thus make the teeth of the pinion stationary. 53 is a bracket secured as at 54 upon the lower end of the rear guide member 23 and having a bearing 55 for a spindle 56. A lever 57 fixed upon the spindle 56 is situated in front of the guide member 19 to be actuated by the groove follower in a manner to be explained. An arm 58 fixed upon said spindle 56 is adapted to engage the head 52 of the rod 50 at the right in Fig. 1 when said lever is so actuated to depress said rod and thus remove its upper end from a depression 47. An arm 59 fixed upon said spindle 56 is adapted to simultaneously actuate a long link 60 extending transversely of the frame and pivoted to a lever 61 itself pivoted as at 62 to a part of the frame and having an upper portion 63 adapted to engage the head 52 of the rod at the left in Fig. 1 when said lever 57 is actuated in the manner briefly stated to

depress said rod and thus similarly remove its upper end from a depression 47. Clearly, immediately upon the release of said rods 50 from the depression 47, the weight of the 5 plate at the station or location 34 and the weight of the plates in the storage space 29 causes the escapement pinions 44 and 45 to be rotated as a unit. The arrangement is such that immediately after the rods 50 are 10 removed from the depressions 47, the lever 57 is returned, in a manner to be made clear, to its position releasing the heads 52 of said rods, so that the springs 51 can act and said rods can enter the next adjacent depressions 15 47 and thus again lock the pinions as before. Clearly, a quarter-return of the escapement pinions 44 and 45 releases the master plate from the station or location 34 and releases a single plate only from the bottom of the 20 storage space 29, which released plate falls immediately to the station or location 34 where it is retained by the pinions 45 in the manner as already stated until the lever 57 is again actuated.

25 Mechanism is provided for carrying the master plates which have been moved by gravity out of the way 33 back to the storage space 29, this mechanism being adapted to deposit each plate as returned to the storage 30 space directly on top of plates at the time in said storage space and so positioned that the master groove of each plate will be at the side of the way 33 adjacent the groove follower when the plate again reaches the station or location 34 in its regular succession 35 through the machine.

Numeral 64 indicates a conveyor belt for the master plates which is upon the upper idler roll 65 mounted upon shaft 66 in the 40 frame side walls 12 and the lower driven roll 67 fixed upon the shaft 68 also mounted in the frame side walls. The lower portion 69 of the conveyor belt is directly below the way 33 and is preferably almost horizontal, 45 and curved guides 70 secured as at 72 upon a member 71 attached to the base 11 cause said conveyor belt to curve upwardly and rearwardly as indicated at 73, the upwardly and rearwardly curved part of said belt 50 merging in a vertical part 74. 75 is a motor having a driven shaft 76 with bevel gear 77 engaging a bevel gear 78 fixed upon a shaft 79 mounted in any suitable manner in the frame. A small sprocket 80 fixed upon said shaft 79 carries a chain 81 which rides over a small sprocket 82 fixed upon the shaft 68 to continuously rotate the roll 67 to drive the conveyor belt in the direction of the arrows as shown in Fig. 2. 83 denotes rows 55 of hooks extending transversely upon the conveyor belt.

When a master plate is released from the way 33 it falls to the conveyor belt in about the fashion as disclosed in Fig. 2, the rearwardly curved portion 22 of the front guide

member 19 insuring that the lower or forward end of the plate will rest upon the conveyor belt between its curved guides 70. Now, as the conveyor belt advances, the lower or forward end of said plate is advanced 70 with it, and the plate is thus caused to move to and past the oblique position as in Fig. 2 to cause the whole of the plate to fall upon the conveyor belt in front of the next succeeding row of hooks of said belt, which 75 hooks pick said plate up and carry it upwardly as very clearly illustrated. 84 represents a curved stripper secured as at 85 upon the top wall 14 of the frame and in the path of the upwardly conveyed plates, the stripper being adapted to push each plate from the hooks 83 of the conveyor belt as the same advances and cause the plate to enter the storage space 29 in the manner very clearly disclosed at the upper portion of Fig. 2, it 80 being apparent that the plate will be deposited directly on top of other plates in the storage space and positioned so that its master groove will come at the front side of the way 33 when the plate next reaches the station or location 34.

There is in the machine a groove follower 86 and means for propelling the follower along the master groove 31 of a plate 30, the structure of the groove follower and its 95 propelling means being more clearly disclosed in Figs. 1 to 4.

Numerals 87 and 88 indicate, respectively, upper and lower cross-rods which extend the width of the machine and are supported 100 upon the side walls thereof as indicated at 89. 90 is a follower carrier which may include parallel, vertical rods 91 the upper ends of which are fixed to a yoke 92 slideable along the cross-rod 87 and the lower ends 105 of which are fixed to a similar yoke 93 slideable along the cross-rod 88, the rods 91 and the yokes 92 and 93 all together comprising a unit freely movable transversely of said frame, and the cross-rods 87 and 88 together 110 comprising a carriage for said unit. The follower carrier also includes a block 94 mounted upon said rods 91 to be freely movable vertically theron. As disclosed more clearly in Fig. 3, the block 94 has 115 associated with it a portion of the follower propelling means. Of this means, 95 is a cylindrical member rotatably arranged in said block and having a cavity 96 in one of its end portions which receives the groove follower 86. A coil spring 97 in said cavity and engaging a head 98 upon the follower tends to press the same outwardly away from the member 95, and a pin 99 upon the follower head and entering an elongated 120 slot 100 in the member 95 fixes the follower against turning movement in said member. The member 95 has a bell crank lever 101 pivoted upon its other end portion and fixed 125 against turning movement relatively to said 130

member. A leaf spring 102 is fixed to one arm of the bell crank lever as at 103 and extends in angular direction from the member 95 and follower 86, the free end 104 of said spring 102 being adapted to engage under spring tension a comparatively soft surface of a suitable vertical thrust wall 105 fixed in any suitable manner upon the frame and preferably in front of and parallel with the guide member 19.

The groove follower 86 has an outer end portion 106 adapted to ride in the master groove 31, said outer end portion being of thickness to nicely enter the groove and being 15 of breadth slightly greater than the width of the groove. See Fig. 4. The leaf spring 102 is in the plane of the breadth of said outer end portion. It will be evident that the groove follower 86 would follow a groove 20 to pass a location where the groove follower crossed a different groove or a different part of the same groove.

A rotatable pulley 107 is mounted upon the member 95 between the block 94 and the 25 arm 108 of the bell crank lever opposite that having the spring 102, and said pulley is provided with a hump or protuberance 109 adapted to strike the arm 108 once for each rotation of said pulley 107 to flex the leaf 30 spring 102 and cause it to be thrust against the wall 105. The arrangement is such that the free end 104 (which may be pointed) firmly grips the wall 105 during the thrusting action against the wall produced by the 35 striking of the protuberance 109 with the arm 108, to frictionally resist a tendency of the spring 102, together with the elements associated with the spring, to move in the direction of the thrust; that is to say, to move 40 backwardly, in the direction away from the spring and its free end. Naturally, there is a reaction of the spring directly after it is flexed and thrust against the wall 105, and the reaction tends to move the spring forwardly, in the opposite direction. As disclosed in Fig. 3, the engagement of the free 45 end 104 of the spring 102 with the surface of the wall 105 is such that the wall will not resist this reactionary thrust, and the spring 50 will jump ahead a little, and its free end will again engage the surface of the wall 105 as before immediately at the conclusion of the spring reaction. Evidently, the elements associated with the spring 102 move ahead 55 with it, and continuous rotation of the pulley 107 causes the follower 86 to intermittently move ahead in the master groove, in quick, short steps or jumps, much after the style with which the ordinary individual 60 causes a pen or pencil to advance while writing. It is to be understood that the spring 102 desirably normally engages the wall 105 with sufficient spring pressure to insure that the block 94 will be supported against 65 gravity at any of its working locations regardless

of the position at which the follower 86 may be in the master groove 31; that is to say, the spring pressing engagement of the follower propelling means is sufficient to support the follower and its associated parts 70 against gravity. It is also to be understood that the thrusts exerted upon the spring 102 are to be sufficient to provide reactions capable of moving the follower 86 and its associated parts upwardly and downwardly 75 thus causing the block 94 to move upon the rods 91, and transversely thus causing the unit including the yokes 92 and 93 to move upon the cross-rods 87 and 88. The direction of movement of the follower is dependent only upon the direction of the groove which it follows, and the leaf spring 102 always extends in rearward direction with respect to the movement of the follower, said follower and leaf spring being fixed against turning movement relatively to the member 95, which member from time to time rotates in the block 94 an amount depending upon the curvature of a particular groove 31 in which the follower rides.

In Figs. 5 and 6 I have disclosed a follower propelling means of slightly modified construction. Here the pulley 107' has an arm 110 of irregular shape fixed to its outer surface, as at 111, adjacent its periphery. The arm includes a loop 112 bent about the leaf spring 102' secured directly to the member 95' as at 103', and there is a weight 113 upon the end of the arm. Rotation of the pulley 107' causes the weight 113 to revolve about the leaf spring 102' and the centrifugal force produced causes thrusts to be exerted against the leaf spring. As before, thrusts flexing the spring are resisted by the surface of the wall 105, and the reaction of the spring forces the follower ahead. In the present form of the invention the centrifugal force exerted in direction opposite that tending to flex the spring aids the feeding of the follower ahead, as will be clear. The remainder of the follower propelling means of Figs. 5 and 6 may be as described in connection with the preferred form of the invention.

The pulleys 107 and 107' may be continuously rotated in any convenient manner. As disclosed, 114 indicates a shaft extending from front to rear of the machine, said shaft being rotatably mounted in bearings 115 and 116 upon the front and rear walls, respectively, of the frame. A pulley 117 fixed upon said shaft 114 carries a line 118 which travels over an idler pulley 119 upon a shaft 120 at the opposite side of the machine frame and supported in any suitable manner (see the dotted lines in Fig. 1), the line also traveling over idler pulleys, denoted 121 and 122, upon the yoke 93, an idler pulley 123 upon the yoke 92, and over the pulley 107 or 107' as the case may be. The motor shaft

76 has fixed to it a sprocket 124 carrying a chain 125 which travels upon a sprocket 126 fixed upon the shaft 114. Clearly, rotation of the motor shaft thus causes the line 118 to be driven ahead to continuously rotate the pulley upon the member 95.

A stylus is adapted to travel with the groove follower and its propelling means to reproduce the movements of the follower. 10 A writing surface is situated adjacent the stylus and the stylus may move in contact with the writing surface or in spaced relation thereto.

Of the writing surface as illustrated, 127 indicates an endless belt or curtain upon an upper idler roll 128 the shaft 129 of which extends transversely of the frame and is supported in bearings 130 upon the frame side walls, the belt or curtain also being upon a lower roll 131 fixed upon a shaft 132 mounted in bearings 133 upon said side walls. The shaft 132 is adapted to be driven at predetermined times to advance the endless belt or curtain and then to be brought to rest to 25 present a fresh writing surface for each new master plate at the station or location 34. As disclosed more clearly in Fig. 2, a pulley 134 fixed upon the shaft 132 has a line 135 upon it, which line is also upon a pulley 136 fixed to a sleeve 137 normally idle upon the shaft 114. 138 is a fixed clutch element upon the sleeve 137, and 139 is a movable clutch element upon the shaft 114 and adapted to be actuated to engage the clutch element 138 30 and thus make the sleeve rotatable with the shaft 114. The movable clutch element 139 is actuated by a lever 140 pivoted upon the frame as at 141 and having a fork 142 associated with the movable clutch element 139. A 40 rod 143 mounted in a bracket 144 upon the frame is normally spring pressed, as by a coil spring 145 upon the rod and associated with the bracket, to enter a depression 146 in the roll 131. The end of the lever 140 opposite its fork is pivoted to the rod 143 as at 147 so that said rod normally holds the clutch element 139 away from the clutch element 138 to allow the sleeve 137 to be idle. The rod 143 is provided with a head 148 adapted to 45 be engaged by an arm 149 fixed upon the spindle 56 which carries the lever 57. It is apparent that at times when the lever 57 is actuated, the arm 149 causes the rod 143 to be withdrawn from the depression 146 and this movement of said rod 143 throws the clutch element 139 into engagement with the clutch element 138 to rotate the roll 131 and thus advance the curtain or belt. Before the roll 131 has made a complete revolution 50 the arm 149 releases the rod 143, and the spring 145 causes the rod 143 to enter the depression 146 as it returns to the location of the rod, this movement of the rod simultaneously removing the movable clutch element 139 away from the fixed clutch element 138.

175 is a wall fixed in any convenient manner back of the writing location in the machine.

The stylus could be adapted to itself write upon the endless belt or curtain, or the belt or curtain could be of sensitized material and the stylus could throw a shaft of light upon said material to reproduce the movements of the master groove follower. As disclosed, however, there is a container 150 beneath the roll 131 into which the belt or curtain reaches, and said container is loaded with suitable powder or the like to cover the surface of the belt or curtain. The stylus is adapted to provide a visible reproduction of the movements of the follower by wiping over the 80 surface and removing powder or the like therefrom. See Fig. 1. Clearly, a surface written upon is again covered each time it passes into the powder container, 176 indicating hair or the like adapted to assist in spreading the powder upon the curtain or belt.

The stylus may be associated with the groove follower in any convenient and suitable manner. As disclosed more clearly in Fig. 3, 151 is a tube of preferably stiff material soldered or otherwise secured as at 152 to the lower surface of the block 94. Said tube 151 extends first forwardly from the block as at 153, thence downwardly as at 154, thence again forwardly as at 155, and thence upwardly as at 156, the upwardly extending portion passing through the transverse slot 18. See Fig. 2 wherein 157 represents thin edges engaging the portion 156 of the tube and adapted to present as little friction as possible. 158 represents a wire in the tube 151, the forward portion of the wire being secured as at 159 to the stylus 160, and the rearward portion being secured to a lever 161 pivoted upon the block 94 as at 162. An end of the lever 161 is arranged upon the follower 86, as indicated at 163, so that inward and outward movements of the follower, as allowed by the master groove and as actuated by the coil spring 97, swing the lever 161 upon its pivot. The stylus 160 is arranged in a holder 164 which includes a coil spring 165 back of and engaging the stylus to urge it toward the writing surface. In Fig. 3 the follower 86 is disclosed as in engagement with the deepest part of the groove 31, and the stylus is in engagement with the writing surface. As the follower rides up out of a part of its groove deep enough to allow the coil spring 97 to actuate the lever 161 to in turn actuate the wire 158 to cause the stylus to engage the writing surface, it may ride in a part of its groove which pushes the follower forwardly in the machine and actuates said lever 161 to in turn actuate the wire and remove the stylus from the writing surface, said stylus at the same time being capable of moving ahead with the master groove follower, as will be 110 115 120 125 130

clear. The tube 151 could be differently positioned, but I consider the arrangement described and illustrated as satisfactory, for the reason that the whole of the tube is in a vertical plane, a feature adapted to cause the tube and the stylus to have a steady and regular movement as the groove follower advances.

As will be more clear from Fig. 1, the 10 front guide member 19 is cut away as at 166 so that the follower 86 can enter the master groove 31 of a plate 30. At one side of the cut-away portion of said guide member 19 is a pin 167 against which the 15 lever 57 is normally held by a spring 168 upon the spindle 56 and engaging said lever 57. The guide 19 is grooved directly back of the lever 57, 169 denoting the end of the groove of the guide 19 which the follower 20 86 is adapted to enter, and 170 indicating the end of said groove at which the follower leaves the guide member. It will be seen that the master plate 30 has a part, denoted 171, of its groove in alignment with the part 25 169 of the guide member groove so that as a follower leaves the master plate it can enter the groove of the member 19, and said plate 30 has a part, denoted 172, of its groove in alignment with the part 170 of the guide member groove, so that the follower can return from the groove of the member 19 to a plate. The surface denoted 173 of the guide member which has the groove ends 169 and 170 is preferably 30 beveled so that the follower can very readily ride up out of the master groove of the plate into the guide member groove, or from the guide member groove to a plate at the station or location 34.

40 It will be observed that the lever 57 is only actuated when the follower 86 has left the master groove of a plate 30, so that the plate is clear of the follower when it is released from the station or location 34. It 45 will also be observed that were it desired to utilize but a single plate and reproduce its master groove upon a writing surface again and again, the groove 31 in the plate could be continuous, and the lever 57 could 50 actuate only an arm such as 149 to advance the writing surface; that is to say, the master plate could remain stationary in the machine.

When the traverse by the follower 86 of 55 the groove of a master plate is completed, the follower actuates the lever 57, which in turn actuates all of the arms 58, 59 and 149, the arms 58 and 59 having control over the escapement pinions, and the arm 149 having 60 control over the writing surface, all of which elements operate in the manner hereinbefore fully explained. Also, the follower is adapted to allow the lever 57 to return to its normal position immediately 65 after it is actuated, to thus allow the arms

58, 59 and 149 to return to their normal positions.

In Fig. 7 I have disclosed a master plate 30' with groove 31', the arrangement as in Fig. 1 being reversed; that is to say, the groove entrance is above the groove exit. Also in said Fig. 7 I have disclosed a groove 174 in the guide member 19' of tortuous passage adapted to allow the follower to successively engage the lever 57' to actuate 75 said lever. Such an arrangement provides for advancing the writing surface a plurality of steps instead of a single step, and provides for the feeding of a plurality of plates past the follower receiving station or location at the completion of the traverse by the follower of the groove of a plate. Clearly, the plurality of plates so advanced will fall to the conveyor on top of each other, but the hooks thereof are constructed 80 to return a single plate at a time to the storage space. As a plate is carried along the plate above it then rests upon the conveyor ready to be engaged by the hooks. Some of the plates could, obviously, be blank 85 plates.

Having thus fully described the invention, what I claim as new and desire to secure by Letters Patent is:

1. In a machine of the character described, a plate having a master groove, a groove follower, means for periodically imparting thrusts to the follower to propel it along the groove step by step; and means associated with the follower to reproduce 95 its movements.

2. In a machine of the character described, a plate having a master groove, a groove follower, means for periodically imparting thrusts to the follower to propel it along the groove step by step, means associated with the follower to reproduce its movements, and a surface upon which said means is adapted to make visible said follower movements.

3. In a machine of the character described, a plate having a master groove, a groove follower, means for periodically imparting thrusts to the follower to propel it along the groove step by step, a stylus associated with the follower to reproduce its movements, a surface which the stylus is adapted to engage to make visible the follower movements, and means whereby the stylus can be out of engagement with said surface.

4. In a machine of the character described, a plate having a master groove, a groove follower, means for propelling the follower along the groove of the master plate, and means adapted to travel with the groove follower to reproduce its movements, said groove follower being of thickness to nicely enter said groove and of breadth greater than the width of said groove.

5. In a machine of the character described,

a plate having a master groove of varying depth, a groove follower, a spring adapted to urge the follower into engagement with the base of said groove, means for propelling the follower along the groove, a stylus associated with the follower to reproduce its movements, a surface adjacent the stylus, and an operative connection between the groove follower and stylus whereby the stylus can engage said surface to make visible thereon the movements of said follower or can travel in spaced relation to said surface, said operative connection comprising a tube movable with said follower propelling means, a wire in said tube and secured to the stylus, and a pivoted lever movable with said follower propelling means, said lever being connected to said wire and to said follower.

6. In a machine of the character described, 20 a grooved master plate, a follower adapted to ride in the groove of said plate, means movable with the follower to reproduce its movements, and means for propelling the follower along said groove, said means including a block mounted to have universal movement in a plane, a member rotatably mounted in said block, and said follower being secured to said member, a spring secured to said member, a wall which said spring engages, and means for periodically actuating said spring to thrust it with greater force 30 against said wall.

7. In a machine of the character described, 35 a grooved master plate, a follower adapted to ride in the groove of said plate, means movable with the follower to reproduce its movements, and means for propelling the follower along said groove, said means including a block mounted to have universal movement in a plane, a member rotatably mounted in said block, said follower being secured to said member, a spring secured to said member, a wall which said spring engages, and a 40 rotatable pulley upon said member and having means for periodically actuating said spring to thrust it with greater force against said wall.

8. The combination as specified in claim 6, 50 wherein the follower is of thickness to nicely enter said groove and of breadth greater than the width of said groove, and said spring is in the plane of the breadth of said follower.

9. In a machine of the character described, 55 a plurality of grooved master plates, a container for said plates, including means defining a station, means for separately feeding each plate from said container to a position of rest at said station, a groove follower 60 adapted to ride in the groove of each plate while at said station, means for propelling the follower along each plate groove, means for releasing each plate from said station after the follower has completed its traverse 65 of the groove of said plate, and means for

feeding each plate back to said container in position to again be fed to said station in its regular order of succession.

10. In a machine of the character described, 70 a plurality of grooved master plates, a container for said plates, including means defining a station, means for separately feeding each plate from said container to a position of rest at said station, a groove follower adapted to ride in the groove of each plate 75 while at said station, means for propelling the follower along each plate groove, means for releasing each plate from said station after the follower has completed its traverse of the groove of said plate, means for feeding each plate back to said container in position to again be fed to said station in its regular order of succession, a stylus movable with said follower to reproduce its movements, a surface upon which the stylus is adapted to make visible the follower movements, and means for advancing said surface at the completion of the traverse by the follower of the groove of a master plate and for bringing said surface to rest to present a fresh writing 80 90 surface to said stylus.

11. The combination as specified in claim 9, wherein the means for feeding the plates to and from said station consists of interconnected units adapted to release a plate from said container whence it can move by gravity to said station and adapted to simultaneously release a plate at said station, and wherein the means for feeding each plate back to the container comprises a conveyor 95 belt to which said plates can move by gravity when released from said station.

12. The combination as specified in claim 10, wherein the means for feeding the master plates to and from said station and for advancing the writing surface are under the control of a single lever adapted to be actuated by said groove follower.

13. In a machine of the character described, 110 a grooved master plate, a groove follower adapted to traverse the groove of said plate, means forming a station at which the groove of said plate is adapted to receive said follower, said station including a groove the ends of which are adapted to coincide with the ends of the groove of the master plate, means for propelling the follower along the groove of said master plate and said station, and means adapted to be actuated by said follower while in the 115 groove of said station to release said master plate from said station.

14. In a machine of the character described, 120 a plurality of grooved master plates, a groove follower adapted to traverse the groove of each plate, means forming a station at which the groove of each plate is adapted to successively receive said follower, said station including a groove the ends of which are adapted to coincide with the ends 125 130 of

- of the groove of the master plate, means for propelling the follower along the grooves of said master plate and said station, and means adapted to be actuated by said follower while in the groove of said station to release a master plate from said station and to allow a different master plate to be fed to a position of rest at said station with its groove ready to receive said follower.
- 10 15. The combination as specified in claim 13, wherein the groove of said station has its ends in a surface of said station which slants toward said master plate.
16. In a machine of the character described, a plate having a master groove, a groove follower of thickness to nicely enter said groove and of breadth greater than the width of said groove, means for propelling the follower along the groove of the master plate, said follower propelling means exerting its driving force approximately in the

plane of the breadth of said follower, and means adapted to travel with the groove follower to reproduce its movements.

17. In a machine of the character described, a plate having a master groove, a groove follower, means for periodically imparting thrusts to the follower to propel it along the groove step by step, and means associated with the follower to reproduce its movements, said groove follower being of thickness to nicely enter said groove and of breadth greater than the width of said groove, and said follower propelling means exerting its thrusts approximately in the plane of the breadth of said follower to drive the follower ahead.

Signed at Bridgeport, in the county of Fairfield, and State of Connecticut, this 21st day of November, A. D., 1925.
